(57) **CLAIM**

The ornamental design for an asphalt dipper, as shown and described.

DESCRIPTION

FIG. 1 is a side perspective view of an asphalt dipper; FIG. 2 is another side perspective view of the asphalt dipper of FIG. 1;

FIG. 3 is a right side view of the asphalt dipper of FIG. 1; FIG. 4 is a left side view of the asphalt dipper of FIG. 1; FIG. 5 is a back view of the asphalt dipper of FIG. 1; FIG. 6 is a front view of the asphalt dipper of FIG. 1; FIG. 7 is a top view of the asphalt dipper of FIG. 1; and, FIG. 8 is a bottom view of the asphalt dipper of FIG. 1. The broken lines illustrate a break in the length of the asphalt dipper that forms no part of claimed design.
